UNITED STATES PATENT OFFICE

172,202

TUMBLER RACK

Perry E. Stevenson, Minneapolis, Minn.

Application October 29, 1951, Serial No. 17,144

Term of patent 14 years

(Cl. D44—29)

To all whom it may concern:

Be it known that I, Perry E. Stevenson, a citizen of the United States, residing in Minneapolis, county of Hennepin, and State of Minnesota, have invented a new, original, and ornamental Design for a Tumbler Rack, for which the following is a specification, reference being had to the accompanying drawings, forming part thereof.

Figure 1 is a top plan view of a tumbler rack showing my new design;

Figure 2 is an end elevational view thereof;

Figure 3 is a side elevational view thereof; and Figure 4 is a perspective view thereof.

I claim:

The ornamental design for a tumbler rack, as shown.
